UNITED STATES PATENT OFFICE.

HENRY P. FEISTER, OF PHILADELPHIA, PENNSYLVANIA, ASSIGNOR TO
MARTIN NIXON AND WILLIAM H. NIXON, BOTH OF SAME PLACE.

PAPER BAG.

SPECIFICATION forming part of Letters Patent No. 325,922, dated September 8, 1885.

Application filed February 2, 1885. (No model.)

To all whom it may concern:

Be it known that I, HENRY P. FEISTER, a citizen of the United States, and a resident of Philadelphia, Pennsylvania, have invented 5 certain Improvements in Paper Bags, of which the following is a specification.

My invention consists of a paper bag folded and pasted at the end to form a bottom, the seams of which are invisible, as hereinafter 10 claimed and specified.

In the accompanying drawings, Figure 1, Sheet 1, is a side view of the blank; Fig. 2, also a side view representing a slightly-modified form of blank; Figs. 3, 4, 5, and 6, perspective views, showing the mode of folding the end of the blank to form the bottom of the bag; Figs. 7 and 8, perspective views of the bags as they appear when collapsed for storage or transportation; Figs. 9, 10, and 11, 15 Sheet 2, perspective views illustrating the advantage of the modified blank, Fig. 2.

The blank to be formed into a bag consists of a section, A, of a quadrangular tube of paper, the term "quadrangular" being intended 20 to apply to the blank, whether it is distended or collapsed, but when distended it has a tendency to assume a quadrangular or an approximately quadrangular form, because it has been creased by subjecting it to a former of corresponding form. The tube has been so severed 25 while distended that it has an inclined termination, either as shown by the straight line x in Fig. 1 or by the curved line y in Fig. 2, the term "inclined" being intended to apply to 30 both.

The operation which I am about to describe 35 will be performed by a machine which will hereafter form the subject of an application for a patent; but I will explain here how the bottom of the bag may be formed by hand, discarding for the time being the view, Fig. 2, and referring to Figs. 1, 3, 4, 5, 6, 7, and 8, Sheet 1.

We will suppose that the blank A, Fig. 1, 40 is on the former D, a portion, M, of the blank projecting beyond the end a of the former, and this projecting portion being composed of the two angular and opposite sides, m m' , the bottom n , and the top, n' , which is necessarily 45 much narrower than the bottom, (see Fig. 3.)

owing to the inclined direction in which the tube has been severed. The first operation is to push the angular sides inward and against the end a of the former, as shown in Fig. 4, then to turn the narrow top n' down and fold the bottom against it, (see Fig. 5,) paste being applied to secure the bottom n to the folded parts. The bottom n of the portion M is of such size that when pasted to the other folds it conceals or nearly conceals the same. The 55 end a of the former D, the said end being at right angles to the sides, forms the backing which determines the limit of the above-described folds and determines the quadrangular shape of the bottom of the bag, which is 60 now withdrawn from the former.

It should be stated here that I prefer to crease the opposite sides of the quadrangular paper tube from which the sections or blanks are severed on the dotted lines t , so that when 70 the bags are withdrawn from the former they may be readily collapsed, as shown in Fig. 7, or as illustrated in Fig. 8, so as to be packed in a small compass for storage and transportation.

Referring now to the blank A', Fig. 2, Sheet 1, and the views, Figs. 9, 10, and 11, Sheet 2, it will be seen that the end of the quadrangular blank has been severed from the paper tube on a curve, y . While the end 80 of this blank is folded to form the bottom of the bag in the same manner as the blank A, it possesses over the latter an advantage which may be explained as follows:

At the corners w w , Fig. 10, where the top 85 fold, n , overlaps the infolded sides m m' , there are necessarily three thicknesses of paper, and when the blank is made in the manner shown in Fig. 1 the bottom n will have at the corners two thicknesses of paper to bear against 90 the thick corners w w ; but when the end of the blank is made on a curve the portions of the sides m m' which are folded against the inner side of the bottom are so inclined as to escape the folds at the corners w w . (See 95 Fig. 10.) This may be further explained in connection with Fig. 11, which is an end view of the bag, with the bottom fold, n , partly turned down to expose the inner sides of the same and show the fold n' and parts of the 100

side folds. Inclined ridges are formed at the corners w w , the shaded portions showing where there are three thicknesses of paper.

The inner folds, m m' , of the bottom are such as to escape these ridges when the said bottom is turned up against the fold n' ; but should the tube be severed on a straight inclined line, as in Fig. 1, the condition of the folds m m' against the inner sides of the bottom would be that shown by dotted lines in Fig. 11, and these folds would overlap the above-mentioned inclined ridges, and there would be an addition of two thicknesses of paper to the thicknesses already existing at the points indicated, and these five thicknesses of paper at two points have a tendency to interfere with the

easy pasting of the bottom fold, n , to the other folds. For these reasons, while the blank A, Fig. 1, can be effectually closed to form a bottom, I much prefer the blank A'.

I claim as my invention—
A paper bag composed of a quadrangular tube inclined at the end, and having a bottom consisting of folds m m' and n n' , substantially as specified.

In testimony whereof I have signed my name to this specification in the presence of two subscribing witnesses.

HENRY P. FEISTER.
